UNITED STATES PATENT OFFICE.

CHARLES E. SCRIBNER, OF CHICAGO, ILLINOIS, ASSIGNOR TO THE WESTERN ELECTRIC MANUFACTURING COMPANY, OF SAME PLACE.

ELECTRICAL SWITCH-BOARD.

SPECIFICATION forming part of Letters Patent No. 254,389, dated February 28, 1882.

Application filed December 22, 1881. (No model.)

To all whom it may concern:

Be it known that I, CHARLES E. SCRIBNER, of Chicago, Illinois, have discovered a certain new and useful Improvement in Switch-Boards, 5 of which the following is a full, clear, concise, and exact description.

My invention relates to that class of switch-boards in which horizontal strips and vertical rods or bars are used in combination with plugs 10 or pegs for making the connections.

As used at the central office of a telephone-exchange each vertical rod should be connected to ground through an annunciator, and the current sent from any given station passes 15 from the rod belonging to the line of the station through the annunciator of the rod and to ground.

Heretofore, in order to answer the call, it has been necessary to first remove the ground- 20 peg and then insert the peg, so as to connect the bar with the strip to which the signaling-battery is connected. After the order from the subscriber has been received in the usual manner the plug must be again removed and 25 inserted, so as to connect the rod with a free strip, with which connection is made with the rod of the subscriber called for.

My improvement consists in pivoting the rods so that they may be connected or disconnected from the ground of the annunciator or battery, as the case may be, by simply turning the rods.

In the drawings, Figure 1 is a front elevation of a portion of a switch-board embodying 35 my invention. Three rods, *a b c*, are shown, each in a different position from the other two. The horizontal strips *d e f* are arranged in the usual manner.

Fig. 2 is a plan showing the connections of 40 the annunciators and the battery with the rods. Arms *g h i* are attached to the rods. When rod *a* is in the position shown its arm *g* is in contact with point *k* of the ground-line, in which is included the coils of the electro-magnet 45 of the annunciator *l*. All rods are thus

connected to ground except when in active use, and a subscriber, by sending a current to line, operates the annunciator of his line, thus informing the central office of his call. The attendant, on seeing an annunciator fall, inserts 50 a peg in a hole of the rod opposite any free strip, and, using the peg as a lever, turns the rod so as to break contact with the annunciator and connect with the battery. The arm *h* of rod *b* is shown thus connected with contact-point *n* of the battery. The call of a subscriber is thus answered, and the operator at once turns the rod back so as to disconnect from the battery, but not far enough to connect with the annunciator, and then inserts the peg, so 55 as to connect with the free strip. The peg is shown thus inserted, connecting rod *c* and strip *f* of Fig. 2. The switchman may then connect his telephone to the rod, and, having received the order, call up the subscriber asked for by 60 connecting his line with the battery, as before described. After the called subscriber is thus summoned his rod is turned back and the peg is inserted, so as to connect his rod with the strip to which the calling subscriber has been 65 connected.

I claim—

1. The combination of movable bars *a b c*, for the subscribers' lines, and transfer-strips *d e f*, having plug-holes at the intersections, contact-arms *g h i*, and two contact-points for each arm, one for closing the circuit through the annunciator to ground, the other for connecting with the signaling-battery, substantially as shown and described. 75

2. The combination, substantially as herein described, of upright bars intersecting the transfer-strips, with contact arms, one attached to each bar, and pegs for connecting the line of any given bar to a transfer-strip.

CHARLES E. SCRIBNER.
